UNITED STATES PATENT OFFICE.

TOOMBS O. POPE, OF COLUMBUS, GEORGIA, ASSIGNOR TO DRAPER COMPANY, OF HOPE-DALE, MASSACHUSETTS, A CORPORATION OF MAINE.

SHUTTLE-GUARD FOR LOOMS.

1,077,553.

Specification of Letters Patent.

Patented Nov. 4, 1913.

Application filed February 15, 1913. Serial No. 748,596.

To all whom it may concern:

Be it known that I, TOOMBS O. POPE, a citizen of the United States, and resident of Columbus, county of Muscogee, State of Georgia, have invented an Improvement in Shuttle-Guards for Looms, of which the following description, in connection with the accompanying drawing, is a specification, like characters on the drawing representing like parts.

This invention has for its object the production of simple and effective means for preventing a shuttle in flight from being deflected and thrown out of the loom, breaking by contact of the rapidly moving shuttle with other adjuncts of the loom being thereby eliminated.

In some cases great damage is inflicted upon filling-forks, feelers, temples, and shuttles by the failure of the shuttle to maintain its proper path when shot across the lay, due principally to a lifting of the leading end of the shuttle as it approaches the mouth of a shuttle-box, and notwithstanding the use of the well-known form of shuttle-guide made as a stout metal rod carried by the reed-cap and extended lengthwise thereof above the shuttle path.

In accordance with my present invention I mount a shuttle-guard adjacent the mouth of the shuttle-box and overhanging the shuttle path, and herein the guard is shown as mounted securely upon the reed-cap, the guard having a deflecting face which is inclined downwardly toward the mouth of the box.

Should the tip of the incoming shuttle tend to lift it will strike the deflecting face of the guard and thereby will be directed downward to its proper path, effectually preventing the shuttle from being thrown out.

In the practical embodiment of my invention herein selected for illustration the novel features of my invention will be fully described in the subjoined specification and particularly pointed out in the following claim.

Figure 1 is a transverse section of a portion of an automatic filling-replenishing loom, taken on the line 1—1, Fig. 2, with one embodiment of my invention applied thereto; Fig. 2 is a front elevation of the lay and reed, broken out centrally and at the ends to economize space, showing my

novel shuttle-guards adjacent the inner ends or mouths of the shuttle-boxes; Fig. 3 is a top plan view of a portion of a shuttle-box, the lay, and the reed-cap, showing the shuttle-guard overhanging the shuttle path; Fig. 4 is a perspective view of the guard, detached.

Referring to the drawing, the lay A, reed B and reed-cap C, the usual guard-rod D on the reed-cap, the shuttle-boxes E, F, Fig. 2, and the hopper stand G, Fig. 1, forming a part of the replenishing mechanism, may be and are all of well known construction familiar to those skilled in the art, the guard rod being secured at its ends to the reed-cap by suitable fastenings H and as usual said rod is bent downward toward the race-way of the lay, at D^x, the cap C having the usual bevel C^x. This rod is designed to hold the shuttle in the loom, but frequently fails of its purpose, the flying shuttle up-tilting and being thrown out from the loom over the top or cover-plate of the shuttle-box, through the space between the part D^x of the guide and the mouth of the box. If

the mis-directed shuttle strikes a temple, filling-fork, or feeler, the part struck is almost certain to be broken and often the shuttle itself is smashed or badly damaged. To obviate such accidents and to prevent the shuttle from being thrown out under any conditions I have provided a shuttle-guard, mounted adjacent the mouth of the shuttle-box and having an inclined shuttle-directing or deflecting face.

In the present embodiment of my invention the guard comprises a flat metal body 1 having on its upper side an upright ear or flange 2, provided with apertures 3, Fig. 4, for the reception of suitable attaching members, and the body 1 is slotted for a portion of its length at 4 adjacent the base of the flange. The plate increases in width from its slotted end to its outer, lower end 6, as shown clearly in Fig. 3. The guard is set up adjacent the mouth of the shuttle-box, and as herein shown by attaching the flange 2 to the front side of the reed-cap in any suitable manner, as by screws 5, the bent of the guide D, D^x entering the slot 4 while the bevel C^x of the reed-cap permits the body 1 to extend under the said cap practically back to the reed, as shown in Fig. 1, said body being set diagonally and downwardly inclined

at its outer end toward the mouth of the shuttle-box, Fig. 2. The guard is set or mounted low enough on the reed-cap to prevent the point of the shuttle from getting in between the lower edge 6 of the guard and the top plate of the adjacent shuttle-box, Fig. 2.

If the shuttle approaching the box E, Fig. 2, should lift up its point would strike the under or deflecting face of the body 1 of the guard and would thereby be directed downward and returned to its proper path on the lay. A similar guard, but reversed as to position and inclination, is set at the left hand end of the loom, adjacent the mouth of the box F, Fig. 2, and about one-half inch to the right of the usual filling-fork, the guard being so positioned that the point of the shuttle cannot lift high enough to strike the top of the box, or jump over it.

Obviously the guards will never be touched by the shuttle so long as the latter moves in its proper path, but if the shuttle lifts up as it approaches a shuttle-box the shuttle point will strike the inclined face of the guard and will be deflected and forced downward so that it must resume substantially its normal path and enter the box properly.

As shown in Figs. 1 and 3 the width of the deflecting portion or body 1 of the guard is wide enough to extend well over the path of the shuttle so that the latter when tilted cannot, under the most aggravated condi-

tions, fail to engage and be deflected by the guard and thereby be returned to proper position.

The construction is very simple, it can be made at a low cost and applied readily and quickly, and adds but little to the weight of the lay.

Changes or modifications in details of construction may be made by those skilled in the art without departing from the spirit and scope of my invention as set forth in the annexed claim.

Having fully described my invention, what I claim as new and desire to secure by Letters Patent is:

In a loom, a lay having a shuttle-box and a reed-cap, and a longitudinally extended guide-rod on the cap, combined with a shuttle-guard comprising a flat deflecting portion slotted to embrace the guide-rod, and an upturned flange on said deflecting portion, fixedly secured to the reed-cap, said deflecting portion overhanging the shuttle path and being inclined downward toward the mouth of the box to prevent the shuttle from flying out of the loom.

In testimony whereof, I have signed my name to this specification, in the presence of two subscribing witnesses.

TOOMBS O. POPE.
